CONTROL SYSTEM FOR HYDRAULIC MOTORS

Thomas F. Stacy, Piqua, Ohio, assignor to The French Oil Mill Machinery Company, Piqua, Ohio

Application May 20, 1942, Serial No. 443,766

5 Claims. (Cl. 60—52)

1

This invention relates to control systems for hydraulic motors such as hydraulic presses, and is in the nature of a continuation in part of my prior copending application No. 262,709, filed March 18, 1939, now Patent No. 2,367,241, issued January 16, 1945.

It has been proposed to have a pilot system operate a main valve which controls the advance and retraction of a working member, such as a hydraulic ram or platen, in which the pilot system includes a valve that is internally balanced as to pressure, and which directs the pilot operating fluid to hydraulic means for operating the main valve. When the advancing pressure on the working member reaches a predetermined pressure, a pressure responsive hydraulic device is utilized to move the pilot valve in a direction to reverse the direction of travel of the working member, but as the pressure builds up gradually, the pilot valve is operated gradually. Since the pressures at the time of reversal are relatively high, injury to the pilot and main valves by such gradual operation often results, and the action is not as prompt as it should be.

An object of the invention is to improve and simplify pilot operated controls for hydraulic motors, and particularly for hydraulic presses, with which danger of injury to the valves through slow movement thereof will be avoided, which will require a minimum number of parts, which will have maximum flexibility of control, and which will be relatively trouble-free and relatively simple and inexpensive.

Another object of the invention is to provide an improved control system for hydraulic motors and presses, which will eliminate the use of mechanical latches and slowly opening contacts in electrical circuits, which will give maximum freedom and flexibility of control, and which will avoid shock in the hydraulic control system upon reversal of the direction of travel of the working member, when the reversal occurs immediately after a relatively high pressure has been exerted on the working member.

Another object is to provide an improved control system in which the delivery of the pump will be automatically reduced during a reversal of direction of travel of the working member of the motor, and then increased to speed the reversal.

Other objects and advantages will be apparent from the following description of an embodiment of the invention, and the novel features will be particularly pointed out hereinafter in connection with the appended claims.

2

In the drawing:

Fig. 1 is a sectional elevation showing, somewhat diagrammatically and schematically, parts of a hydraulic motor, and a control and operating system therefor constructed in accordance with this invention; and

Fig. 2 is a fragmentary diagram illustrating a slight modification of the system shown in Fig. 1, in which a bleeder port is substituted in place of a check valve.

In the embodiment of the invention illustrated in Fig. 1, the hydraulic motor is in the nature of a hydraulic press having a head 1 open at its lower end to slidably receive a ram or piston 2 which terminates within the head 1 in a piston head 3 that closely fits and reciprocates in the chamber within the head 1. The chamber 4 at the upper end of the head 1 may be considered an advancing cylinder for forcing the piston head 3 downwardly or in an advancing direction, and the chamber 5 below the piston head 3 may be considered as a retracting cylinder for forcing the piston head 3 upwardly or retracting it. The chamber 5 is also sometimes called a "pull-back cylinder" and it may be a separate ram entirely outside the chamber within the head 1, but connected to the working member or plate 6 which is carried on the piston or ram 2. In the particular illustration, the platen 6 descends during an advancing stroke or movement, and is elevated when retracted or returned to its initial position.

Any suitable source of operating fluid or liquid under pressure may be employed for operating the hydraulic motor, but preferably the source of operating fluid is a pump 7 of the variable delivery type which is connected at its intake side by a pipe 8 to a reservoir 9 for fluid such as oil. The output side of the pump 7 is connected by a pipe 10 to a port 11 in the casing of a main valve 12. The valve 12 includes a valve chamber 13 in which reciprocates a valve element 14 having spaced lands 15 and 16 within the chamber 13.

A helical compression spring 17 acting between one end of the chamber 13 and the land 16 yieldingly urges the valve element 14 in one direction from the position shown by dot and dash lines to the position shown by dash lines in Fig. 1. The valve element 14 has an extension, rod or piston portion 18 extending exteriorly of the chamber 13 and into another and separate chamber 19 in a part which may be integrally attached to the housing of the valve 13. The chamber 19 and rod portion 18 constitute a hydraulic

device which, when fluid pressure is applied to chamber 19, applies a moving force to valve element 14 tending to shift it upwardly in Fig. 1, against the action of the spring 17, into the upper position shown by dot and dash lines in Fig. 1. The position of the valve element as shown by full lines in Fig. 1 is its intermediate position, that is, intermediate the two positions which have just been described. The port 11 is intermediate the lands 15 and 16 when the valve element is in its intermediate position, and the land 16 is beveled at its periphery, as shown in Fig. 1.

When the valve element 14 is in the intermediate position, the beveled edge of the land 16 will be aligned with an annular port 20, and the fluid delivered through the port 11 from the pipe 10 may pass around the land 16 at the annular port 20 and reach an outwardly disposed port 21, which is connected by a pipe 22 to the reservoir 9. The port 20 is connected by a pipe 23 to the advancing cylinder 4. The valve 12 also has a port 24 which is bridged and covered by the land 15 when the valve element 14 is in its intermediate position shown by full lines in Fig. 1, and this port 24 is connected by a pipe 25 to the pull-back or retracting chamber or cylinder 5. The end of the chamber 13 opposite from the spring 17 is provided with a port 26 which is also connected to the pipe 22 leading to the reservoir 9.

The pipe 10 is provided with a choke valve 27 through which all of the fluid reaching the chamber 13 of valve 12 must pass, and this choke may be of any suitable type which creates just sufficient back pressure to provide a working pressure on the pump at all times. A simple pressure relief valve set for a relatively low pressure but opening to pass fluid away from the pump is very suitable for this purpose. When the valve element 14 is in its intermediate position, fluid from the pump 7 passes through the pipe 10 to the chamber 13 of the valve 12, thence back by pipe 22 to the reservoir. Fluid in the retracting cylinder 5 is held against escape by the closing of the port 24 by the land 15.

When the valve element 14 is moved upwardly in Fig. 1, the land 15 will move into a position between the ports 11 and 24 and will uncover port 24, and land 16 will move into a position between ports 20 and 21 and cut off direct communication between those ports. The fluid delivered by the pipe 10 from the pump 7 will then pass through chamber 13 of valve 12 into pipe 23 and thence to the advancing cylinder 4 to cause an advance or descent of the working member or platen 6. When element 14 is in its upper position, the port 24 is uncovered and fluid from the retracting chamber 5 may escape through pipe 25, port 24, lower end of chamber 13, port 26 and pipe 22 back to reservoir 9. The platen 6 will descend under its own weight aided by the fluid delivered from the pump through the pipe 23, and to provide a more rapid advance or descent, a pilot operated, prefill check valve 28 is connected by pipe 29 to the chamber 4 and by a pipe 30 to reservoir 9. The valve element 31 in the check valve opens automatically by reason of the suction in the chamber 4, and fluid is drawn from the reservoir 9 through pipe 30, valve 28, and pipe 29 to fill the space in head 1 that increased with the descent of the piston head 3, as usual in hydraulic presses of this type.

Manual means for operating the valve element 14 may be provided such as by extending the valve element 14 outwardly of the housing of the

valve 12 and providing spaced collars 32 thereon between which the forked end of a lever 33 operates. The lever 33 is pivoted at 34, and by rocking the lever 33, the valve element 14 may be shifted upwardly to cause an advance or descent of the platen 6, or downwardly to cause a return of the platen. Any other manual control for element 14 may be employed. Such manual operation of valve element 14 is advantageously employed when the platen is being inched or advanced by small increments as in setting up dies or work in the press, or wherever a close control of the press for obtaining small movements of the platen is desired. When a full, advance operation of the platen 6 is desired, the valve element 14 is operated against the action of the spring 17 into its upper or advancing position, by the application of fluid under pressure to the chamber 19. Fluid in chamber 19 acts on the extension 18 and hydraulically shifts the valve element 14 upwardly into its advancing position, which is one of its end or limit positions.

The chamber 19 is connected by a pipe 35 to a pilot valve 36 having therein a valve element 37 which is internally balanced as to pressure, so that this valve element will remain in either of its positions into which it may be moved and the pressure of the operating fluid therein will not move the valve element in either direction. The pipe 35 opens into the housing of the valve 36 through a port 38, and a pipe 39, leading from the pipe 18 between the choke valve 27 and the pump 7, opens into the chamber of the valve 36 through a port 40. The valve element 37 carries spaced lands 41 and 42, and when it is in one end position, such as shown in full lines in Fig. 1, the land 41 will be disposed between the ports 38 and 40, and the land 42 will be on the opposite side of the port 40. A drain pipe 43 opens into the ends of the chamber of the valve 36 and leads to the reservoir 9.

When the valve element 37 is in the position shown in Fig. 1, fluid under pressure from the pump passes through pipes 10 and 38 and port 40 into the chamber of the valve 36 between the lands 41 and 42, and since the lands are the same size, the pressure exerted on the valve element will be equal in both directions and will cause no movement of the valve element. Since the land 41 is between the ports 38 and 40, there will be no escape for the fluid delivered to the pilot valve, the port 38 will be in communication with the adjacent end port to which drain pipe 43 is connected, and there will be no fluid pressure in the chamber 19 of the valve. If now the valve element 37 is moved to the left in Fig. 1, so as to place the lands 41 and 42 in the positions shown by dash lines, then the land 41 will be between the port 38 and the adjacent connection to the pipe 43, thereby preventing escape of fluid from chamber 19 to pipe 43, and the ports 38 and 40 will be connected to one another by the space between the lands 41 and 42. Fluid from the pump will then pass through the pilot valve 36 to chamber 19 and force the valve element 14 upwardly against the action of spring 17 into the advancing position to cause a descent or advance of the platen 6. Since the valve element 37 of the pilot valve is internally balanced, it will remain in this position and the pressure of the pump will hold the valve element 14 in this elevated position.

Any suitable means for operating the pilot valve element 37 into the dash line position to cause an advance of the platen 6 may be em-

ployed, but for convenience, this may be accomplished by disposing the core 44 of an electromagnet or solenoid 45 in a position endwise against the valve element 37, so that when the solenoid 45 is energized, the core 44 will be moved endwise and will shift the pilot valve element 37 from the full line to the dash line position in Fig. 1. Current for the solenoid 45 is supplied from line wires L' and L², the circuit being controlled by a normally open switch 46, which is closed and held closed only long enough for the solenoid to move the valve element 37 into the dotted or dash line positions, after which the switch 46 is released and will be automatically opened.

The switch 46 or the circuit of the solenoid 45 may be controlled by any suitable automatic mechanism that one may desire, but since the details of such controls are no part of the present invention, only a simple circuit for the solenoid 45 has been illustrated.

To operate the pilot valve element 37 from the dash line position to the full line position at the end of a desired movement of the platen 6, a fluid responsive device has been provided. For this purpose, a plunger 47 is disposed endwise in axial alinement with the valve element 37, and at the end opposite from the solenoid 45. This plunger is yieldingly urged into retracted position by a suitable retracting means such as by a spring 48 acting between a collar 49 on the plunger 47 and the end of a housing 50 having therein an auxiliary chamber or cylinder 51 through which the plunger 47 extends endwise. The plunger 47 at a point within the chamber 51 is provided with a head 52 which acts as a piston therein. A pipe 53 is connected to the chamber 51 behind the head 52 so that when fluid pressure is supplied to chamber 51 by pipe 53, it will force the plunger 47 to the right and carry the pilot valve element 37 from the dash line position to the full line position, thus returning the pilot valve element to its normal, initial position. This same movement serves to move the core 44 of the solenoid 45 back into its retracted position.

The pipe 53 is connected to the outlet side of a pressure relief valve 54, and the other or inlet side of that valve is connected by a pipe 55 to the pipe 23 leading to the advancing cylinder 4 of the hydraulic motor or press. The pressure relief valve 54 opens to pass fluid from the pipe 23 to the pipe 53, thence to the chamber 51, automatically when the pressure in the pipe 23 exceeds a predetermined pressure for which the pressure relief valve is set, and closes automatically to prevent flow of fluid in the opposite direction therethrough. Since the fluid in the pipe 23 will be under substantially the same pressure as that in the advancing chamber or cylinder 4, the result is that the valve 54 automatically opens when the pressure in the advancing chamber or cylinder 4 exceeds a predetermined value for which the valve 54 is set. When valve 54 opens, fluid passes through valve 54 into the auxiliary cylinder 51 behind the head 52 and forces it to the right against the action of the spring 48 to shift the pilot valve element 37 into the full line position in Fig. 1, where it disconnects the pipes 35 and 38, and vents the pipe 35, thus releasing pressure from chamber 19.

The spring 17 then urges the valve element 14 of the main valve downwardly in Fig. 1 and toward a position in which the land 16 is between ports 11 and 20 and land 15 is between ports 24 and 26. This disconnects the pipe 10 from

the advancing chamber 4 and connects the pipe 23 to the port 21, thus allowing release of fluid from the main or advancing cylinder and its movement back to the reservoir 9. This causes a return of the platen 6 to its elevated position. It is undesirable to have the valve element 14 pass through the intermediate position and into reverse position without stopping, because this causes a severe shock to the hydraulic system, owing to sudden release of the high pressure in the advancing chamber. Such pressures in the advancing chamber often amount to as much as 2500 or 3000 pounds per square inch and the sudden release of such a high pressure, accompanied by the simultaneous application of fluid under the same pressure as received from the pump through pipe 10 to the retracting chamber 5, produces objectionable shocks. This shock is avoided by having the valve element 14 automatically restrained momentarily in the intermediate position and then allowed to continue its movement into reverse position.

Means for accomplishing this shock prevention will now be described. A two-way valve 56 has a chamber 57 in which a valve element 58 reciprocates. The element 58 extends through the housing of that valve along the path of travel of the platen 6, as an outward rod or extension 59. The latter carries a collar 60 slidably therealong but secured thereon in any position, such as by a set screw, so as to be adjustable into different selected positions along the rod 59. The platen 6 has an extension 61 which moves along the rod 59 and at a selected point in the return travel of the platen 6, which position is determined by the setting of the collar 60, the extension 61 picks up the collar 60 and through it shifts the valve element 58 into the position shown in full lines in Fig. 1 against the action of a spring 62. When the platen moves downwardly, the released valve element 58 is shifted downwardly by the spring 62 into its other position.

The housing of the main valve 12 extends beyond the chamber 19 so as to provide a second chamber 63 which is alined with the chamber 19. A piston 64 slidably extends through the partition wall 65 between the chambers 63 and 19, so as to abut against the end of the extension 18 of the valve element 14. The end of the piston 64 which is within the chamber 63 is provided with a head 66, which by engagement with the wall 65 limits the movement of the piston 64 into the chamber 19 beyond the position shown in Fig. 1. The piston 64 can thus shift the valve element 14 into the intermediate position shown in Fig. 1 against the action of the spring 17, but no farther. A rod 67 extends outwardly of chamber 63 from the head 66 of piston 64 and at its outer end carries an adjustable nut 68. A spring 69 is compressed between the nut 68 and the part of the housing in which the chamber 63 is located, so as to yieldingly urge the piston 64 in a direction away from the valve element 14.

A pipe 70 is connected to the outer end of the chamber 63 and to an intermediate port in the valve 56. The valve element 58 carries a pair of spaced lands 71 and 72 arranged on opposite sides of the port opening into the pipe 70. A pipe 73 leads from the pipe 25 to the chamber 57 at a zone immediately adjacent the land 72 when the valve element 57 is in its position shown in full lines in Fig. 1, but in a position to be closed by the land 72 when the valve element 57 is released by the platen 6 and moved by the spring 62 into its other position.

Another pipe 74 opens into the chamber 57 of valve 56 in a position to be closed by the land 71 when the valve element 58 is in its full line position, but in a position to be uncovered by the land 71 and placed in communication with the opening to pipe 70, when the valve element 58 is released and moves downwardly by the action of spring 62. The pipe 74 leads to the pipe 23, which is in communication with the advancing chamber 4. This valve 56 is a two-way valve internally balanced as to pressure, and yieldingly urged into one position when released by the platen but moved into its other position by the platen as the latter approaches a selected position in its return movement. When the platen 6 is retracted and operates the valve element 58 into the position shown in full lines, it places the pipes 70 and 73 in communication with one another so that the pressure in the retracting chamber 5 will be in communication with the chamber 63. This pressure forces the piston 64 upwardly as far as it will go, and thus forcibly shifts the valve element 14 of the main valve 12 into the intermediate position shown in full lines.

The fluid in the chamber 5 will be under pressure at this time because the weight of the platen 6 and piston 2 will tend to carry the platen 6 downwardly, but escape of fluid from the chamber 5 is substantially prevented by the land 15 which closes the port 24. Thus the chamber 63 and its piston 64 which may be aptly designated as a "pressure responsive means," serves to move the valve element 14 into its intermediate position and hold it in that position.

When the platen 6 has descended to some extent and released the valve element 58, the latter is then moved to connect the pipes 70 and 74 so that thereafter until the platen 6 returns, the chamber 63 will be subjected to the pressure in the main advancing chamber 4. During the early part of the descent of the platen 6 after valve 56 operates, there is little pressure in chamber 4 and any fluid in the chamber 63 can escape into the advancing chamber 4 through the valve 56. During descent of the platen 6, valve element 14 is held in its upper position by fluid pressure in chamber 19, and this same pressure in that chamber aids spring 69 in retracting piston 64 as soon as valve element 58 is released by platen 6 and operated by spring 62.

As soon as substantial resistance is encountered by the platen 6, it will not continue to fall of its own weight, but the pump will continue to deliver operating fluid to the chamber 4, the valve element 31 in the check valve 28 will close automatically and pressure will build up in the chamber 4. This pressure is, of course, communicated to the chamber 63 but at that time, the valve element 14 is still held in its upper position by the pressure in the chamber 19. The chamber 63 will have the same pressure as that in the advancing chamber 4. When the pressure in the advancing chamber 4 is sufficient to force the pressure relief valve 54 open, fluid will pass through that valve into the auxiliary cylinder 50 and force the plunger 47 in a direction to operate the pilot valve element 37 and release the hydraulic pressure holding the valve element 14 in its upper position in which it has compressed the spring 17.

The spring 17 then urges the valve element 14 toward its other position, but when element 14 reaches the intermediate position, it is stopped by the plunger 64 which is now held in its full line position by the pressure in chamber 63, and

hence element 14 will be held in this position momentarily while the fluid under pressure in the chamber 4 escapes through the pipe 23 and ports 20 and 21 of main valve 12 to the pipe 22 leading to the reservoir 9. As soon as the pressure in chamber 4 falls sufficiently, the pressure in the chamber 63 which also falls to the same extent, will be overcome by the spring 17 and the valve element 14 will be moved automatically into the reversing position. The platen 6 is then elevated, and the plunger 64 will remain retracted, because the chamber 4 is then under very little pressure, until the platen 6 engages collar 60 and operates the valve 56 to reconnect the pipes 70 and 73, which then places the chamber 63 under the pressure in the retracting chamber. This pressure of the retracting chamber then forces the piston 64 against the valve element 14 and carries the latter into the intermediate position which stops the retraction of platen 6.

After an operation of the plunger 47, it is important to release the fluid from behind the piston head 52, so that the spring 48 can retract it, and this may be accomplished in a simple manner by connecting across the pressure relief valve an ordinary free check valve 75, see Fig. 1, which opens to pass fluid in a direction from the pipe 53 to the pipe 55 but closes automatically to prevent reverse flow. After an operation of the plunger 47, the valve element 14 is operated to cause a retraction of the platen 6 and at such time, the chamber 4 is vented so that there will be no substantial pressure therein. Hence, the fluid from the auxiliary cylinder 50 can escape through the valve 75 and allow retraction of plunger 47 by spring 48.

In Fig. 2, in place of the check valve 75, I have placed a bleeder valve 75a and connection 75b from the pipe 53 to the reservoir so as to allow the escape of fluid from the auxiliary cylinder 50, but of course, such escape is less than the rate of supply through the pipe 53 and valve 54. This is less desirable than the check valve 75.

A pipe 76 connects the pipe 25, to a pilot chamber 77 in the check valve 28, so that when pressure is applied to the retracting chamber 5, the same pressure will be transmitted to the pilot chamber 77. A piston 78 in the chamber 77 is normally retracted by a suitable spring, but when the piston 78 is operated by fluid received from pipe 76, it engages and opens the valve element 31, and hence during the retraction or elevation of the platen 6, fluid can escape not only from the chamber 4 through the valve 12, but the major portion of it can escape through the valve 23 and return directly to the reservoir 9.

A pipe 79 connects the pipe 53 to a pilot chamber 80 provided in the pump 7. A piston 81 reciprocating in the cylinder 80 bears against and operates a yoke shifting lever 82 which is pivoted at 83 to the pump frame and at 84 to one end of a yoke rod 85. The rod 85 is connected to the yoke within the pump, and when the rod 85 is shifted to the right in Fig. 1, it decreases the rate of delivery. A yoke 86 is pivotally connected at the ends of its arms by a pin 87 to the lever 82, and the base of the yoke has an aperture through which loosely passes a rod 88. The connections 84 and 87 are, of course, loose connections which enable the pins 84 and 87 to pursue arcuate paths while shifting the rod 85 and yoke 86 in straight lines. Within the yoke 86, the rod 88 carries an adjustable nut 89, and a spring 90 is compressed between the nut 89 and the

cross part of the yoke 86. The rod 88 passes loosely through an abutment or boss 91 of the pump frame, and a hand wheel 92 is threaded upon the outer end of the rod 88. By rotating the hand wheel 92, the rod 88 may be shifted endwise in either direction to compress or release the spring 90, and the spring 90 yieldingly urges the lever 82 clockwise in Fig. 1 to carry the piston 81 to the right.

When the pressure in the advancing chamber 4 is sufficient to overcome the pressure relief valve 54, the fluid passing this valve 54 not only moves the plunger 47 to shift the pilot valve element 37 into a position to reverse the direction of travel of the platen, but some of it passes through the pipe 79 to the pilot chamber 80 where it forces the piston 81 to the left, and rocks the lever 82 to shift the yoke rod 85 to the right and decrease the rate of delivery of the pump, until the pressure has fallen in the chamber 4 sufficiently, and then spring 90 returns the pump yoke to full delivery position. Thus at the critical time, when the pressure in the advancing chamber 4 is being lowered, the delivery of the pump is decreased preferably to practically no delivery, and then the pump automatically resumes full delivery at the proper time. This aids in preventing shock in the hydraulic system at the time of reversal of travel of the working member.

The pressure at which the pump pilot control operates to cut down the rate of delivery of the pump may be varied by turning the hand wheel 92 to increase or decrease the compression of the spring 90, but the pressure at which the pump will return to full stroke may advantageously be made considerably less than the pressure at which the relief valve 54 will operate, because there will be no operation of the yoke rod 85 to reduce delivery until after the relief valve 54 is opened. If the spring 90 does not require a heavy pressure to overcome it, it will hold the pump 7 on no, or small, stroke until the pressure in the chamber 4 has fallen to the desired extent. The pilot chamber 80 remains responsive to the pressure in the chamber 4 during this fall of pressure in the chamber 4 because at that time, the valve 75 is open, which places the chamber 80 in direct communication with the chamber 4. This gives a decidedly smooth and shockless operation to the control system, when the reversal occurs following the building up of a relatively high pressure in the advancing chamber 4.

It is believed that the operation of the control system will be clear from the foregoing description, but it will be briefly summarized as follows:

Assuming that the parts are in the idle position shown in Fig. 1, an advance or descent of the platen 6 may be started by rocking the hand lever 33, but since the valve element 14 will return to the intermediate position when the handle 33 is released, this is only a temporary control. When one desires to cause a regular cycle of operation of the motor or press, the switch 46 is closed and held closed a moment until the solenoid 45 operates its core 44 and shifts the pilot valve element 37 from the full to the dash line position in Fig. 1. This causes delivery of the fluid from the pump through the pilot valve 36 to the chamber 19, and the pressure in chamber 19 forces the valve element 14 against the action of spring 17 into its upper position to cause an advance of the platen 6. The valve element 14 in that position connects the pipes 10 and 23, and vents the pipe 25 leading to the retracting cham-

ber 5. When this occurs, fluid is released from the chamber 5 and the platen 6 begins its descent. During a small initial movement, the platen releases collar 60 and the valve element 57 is shifted into a position to connect the chamber 63 to the advancing chamber 4.

The check valve 28 will open automatically and fill the chamber 4 with fluid added from the reservoir in addition to the fluid which is delivered by the pump through the pipe 23. When the platen 6 encounters substantial resistance, the valve 28 closes and the platen then continues to advance at a slower rate with a building up of pressure. The pressure in the chamber 4 is, of course, transmitted to the chamber 63, and the same pressure is applied to the chamber 19, but piston 66 being of greater area than piston 64, piston 66 will be elevated to the full line position. When the pressure in the advancing chamber has reached that for which the pressure relief valve 54 is set, the latter opens and passes fluid to the pilot chamber 80 of the pump control and to the auxiliary cylinder 50. The pressure in the latter causes an advance of the plunger 47 and an operation of the pilot valve element 37 back into the full line position.

This releases the pressure in the chamber 19, and thereupon the spring 17 begins to move the valve element 14 downwardly in Fig. 1 towards the position in which it reverses the direction of travel of the platen 6, but piston 64 stops it in the intermediate position until the pressure in chamber 4 has fallen sufficiently to be overcome by the combined pressures of springs 17 and 69, whereupon the valve element 14 automatically continues its movement into full reversing position.

The pressure in the pilot chamber 80 sets the pump for little or no delivery of the pump, so that the full capacity of the return pipes 22 and 23 is available for the escape of fluid from the advancing chamber 4 through the valve 12. Then when the valve element 14 continues its movement into the reverse position the absence of substantial pressure in chamber 4 transmitted to cylinder 80 allows spring 90 to return the pump to full stroke or full delivery. The fluid from the pump then passes at full rate to the chamber 5 to cause retraction of the platen 6. When the platen 6 reaches a selected position in its return, for which collar 60 is set, it operates the valve element 58 to place the pipes 10 and 73 again in communication, and this pressure then forces piston 64 upwardly and through it moves the valve element 14 into the intermediate position, where the delivery of fluid to the retracting chamber 5 is discontinued, and escape of fluid from the chamber 5 at the port 24 prevented. This completes a cycle of operation. It will be understood that during the retraction of the platen 6, however, pressure is transmitted from the retraction chamber 5 to the pilot chamber 77 of the valve 28 which opens the valve 31 to expedite the escape of fluid from chamber 4 and hence aid in retraction of the platen 6.

It will be understood that various changes in the details and arrangements of parts, which have been herein described and illustrated in order to explain the nature of the invention, may be made by those skilled in the art within the principle and scope of the invention as expressed in the appended claims.

I claim:

1. A control system for a hydraulic motor of the type having a working member and hydraulic

means for reciprocating said member including advancing and retracting cylinders, which system comprises a variable delivery pump for supplying operating fluid under pressure, a main valve having a valve element movable between two limit positions through an intermediate position, means connecting said pump, valve and said cylinders, and operable when said valve element is in one limit position for connecting said pump to said advancing cylinder and venting said retracting cylinder, when in its other limit position for venting said advancing cylinder, and connecting said pump to said retracting chamber, and when in said intermediate position for closing said retracting cylinder to prevent escape of operating fluid therefrom, venting said advancing cylinder, and bypassing fluid from the said pump back to the pump, a hydraulic device operable on said valve element for shifting the latter into said one position and holding it in that position, a hydraulic circuit for said device and having therein a two-way pilot valve with a valve element internally balanced as to pressure and operable when in one position for delivering fluid under pressure to said device and when in its other position for discontinuing such delivery and venting said device, selectively controlled means for moving said pilot valve element into a position to cause delivery of fluid to said device, a plunger for shifting said pilot valve element back into its initial position in which it interrupts the delivery of fluid to said device and vents the latter, an auxiliary cylinder in which said plunger moves, a conduit connecting said auxiliary cylinder behind said plunger to said advancing cylinder, a pressure relief valve included in series in said conduit and opening to pass fluid in a direction from said advancing cylinder toward said auxiliary cylinder when a predetermined pressure is reached in said advancing cylinder, said pump having a pilot cylinder and means operated by said pilot cylinder for setting said pump for reduced delivery when a predetermined pressure in said pilot cylinder is reached, means for connecting said pilot cylinder to the discharge side of said pressure relief valve, whereby when said fluid passes to said auxiliary cylinder to move said pilot valve element into position to reverse the direction travel of said member, fluid under the same pressure will pass to said pilot cylinder and set said pump for reduced delivery until the pressure in said auxiliary cylinder falls below that for which said pilot cylinder operated means is set, and a check valve connected in parallel across said pressure relief valve and opening to pass fluid freely in the opposite direction from that passed by the pressure relief valve.

2. A control system for a hydraulic motor of the type having a working member and cylinders for causing advances and retractions of said member, which system comprises a variable delivery pump of the type having a pilot control cylinder and a control operable therefrom which reduces the rate of delivery of the pump automatically when the pressure in said cylinder is above a predetermined pressure, means supplied with operating fluid from said pump and delivering it to said cylinders of said motor to cause movements of said member selectively in opposite directions, pilot means controlling said last named means and having a valve element operable between two positions to determine the direction of movement of said member, means for moving said element into one of said positions, fluid operated means for moving said member

into the other of said positions, a conduit connecting said last means to said advancing cylinder of said motor a pressure relief valve in said conduit and opening to pass fluid to said fluid operated means when a predetermined pressure is reached, a check valve connected in parallel across said pressure relief valve and opening to pass fluid in the opposite directions from that passed by said relief valve, and means connecting said pilot control cylinder to said conduit at the outgoing side of said pressure relief valve, whereby when said pressure relief valve opens said pump will automatically reduce its rate of delivery until the pressure in said advancing cylinder falls below said predetermined pressure for which the pump control is set.

3. In a control system for a hydraulic motor of the type having a working member, a variable delivery pump and a reversing valve connected to said motor and pump in a hydraulic circuit for controlling the delivery of fluid from said pump to said motor to determine the direction of travel of said member, the improved control for said valve which comprises a pilot valve, a source of pilot operating fluid connected to said pilot valve, hydraulically controlled means operatively connected to said pilot valve and said reversing valve for causing movements of the latter between two motor controlling positions and in turn controlled by fluid from said pilot valve, means for causing movement of said pilot valve in one direction, a resiliently retracted, fluid operated device for moving said pilot valve in the other direction, a pipe connected to said circuit and responsive to the fluid pressure urging said member in one direction and connected to said fluid operated device, a pressure relief valve in series in said pipe for passing fluid to said device only when a selected pressure is reached that is greater than that necessary to move said device away from retracted position, whereby movement of said pilot valve when started will be rapid, and means connected to said pipe between said pressure relief valve and said fluid operated device for setting said pump to a decreased rate of delivery upon opening of said pressure relief valve and until the pressure on said working member which opened said relief valve has fallen to a selected extent.

4. In a control system for a hydraulic motor of the type having a working member, a variable delivery pump, and a reversing valve connected to said motor and pump in a hydraulic circuit for controlling the delivery of fluid from said pump to said motor to determine the direction of travel of said member, the improved control of said valve which comprises a pilot valve, a source of pilot operating fluid connected to said pilot valve, hydraulically controlled means operatively connected to said pilot valve and said reversing valve for causing movements of the latter between two motor controlling positions and in turn controlled by fluid from said pilot valve, means for causing movement of said pilot valve in one direction, a resiliently retracted fluid operated device for moving said pilot valve in the other direction, a pipe connected to said circuit and responsive to the fluid pressure urging said member in one direction and connected to said fluid operated device, a pressure relief valve in series in said pipe for passing fluid to said device only when a selected pressure is reached that is greater than that necessary to move said device away from retracted position, whereby movement of said pilot valve when started will be

rapid, means connected to said pipe between said pressure relief valve and said fluid operated device for setting said pump to a decreased rate of delivery upon opening of said pressure relief valve and until the pressure on said working member which opened said relief valve has fallen to a selected extent, and means for releasing pressure from said fluid operated device after an operation thereof and said pressure relief valve has closed.

5. In a control system for a hydraulic motor of the type having a working member and advancing and retracting cylinders in which said member moves, means for delivering fluid under pressure alternately to each of said cylinders and releasing pressure from the other cylinder to determine the direction of travel of said member, the improved control for said delivering means which comprises a pilot valve, a source of operating fluid connected to said pilot valve, a hydraulic motor for operating said delivering means and in turn operated by fluid from said source and controlled by said pilot valve to determine the direction of travel of said member, means for causing movement of said pilot valve in one direction, a resiliently retracted, fluid operated device for moving said pilot valve in the other direction, a pipe connected to said delivering means and responsive to the fluid pressure urging said member in one direction and connected to and

15

5 said device away from retracted position, and means connected to said pipe between said pressure relief valve and said fluid operated device for modifying said delivering means to cause a decreased rate of delivery upon opening of said

10 relief valve until the pressure on said working member which opened said relief valve has fallen to a selected extent.
